J CANDLE AND CANDLEHOLDER

**Salvator Schisano and Generoso F. Schisano,
Brooklyn, N. Y.**

Application March 24, 1939, Serial No. 263,839

6 Claims. (Cl. 67—23)

This invention relates to new and useful improvements in a J-shaped candle and candle-holder.

The invention has for an object the construction of a candleholder characterized by a body having a U-shaped top portion formed with a semi-circular grooved inner face in a manner to hold adjacent J-shaped candles.

10 Still further the body is formed with a flat bottom portion for resting upon a table top or similar surface in a manner to support the U-shaped top portion so that the candles will extend vertically therefrom.

Another object of this invention is the provision of a partition at the bottom of the groove and having overhanging flanges forming sockets for receiving the bottom ends of the J-shaped candles to individually hold each of said candles in a proper position within said U-shaped top portion.

20 top portion.
Still further the invention proposes the provision of a plate for each of the J-shaped candles and mounted in the bottom portion of said groove adjacent the ends of the candles in a manner 25 to be moved to several adjusted positions for holding the candles in different upwardly directed positions.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a candleholder constructed according to this invention.

Fig. 2 is a plan view of the candleholder pedestal.

40 Fig. 3 is a vertical sectional view taken on the lines 3-3 of Fig. 2.

Fig. 5 is a sectional view taken on the line

45 5-5 of Fig. 4.
Fig. 6 is an elevational view of a candleholder constructed according to a still further modification of the invention.

Fig. 7 is a plan view looking in the direction 50 of the line 7-7 of Fig. 6.

Fig. 8 is a view similar to Fig. 6 but illustrating a still further modification of the invention.

Fig. 9 is a vertical sectional view of a candle-holder constructed according to a still further modification of the invention.

Fig. 10 is a view similar to Fig. 1 but illustrating a still further modification of the invention.

Fig. 11 is an enlarged sectional view on the line 11-11 of Fig. 10.

Fig. 12 is a horizontal plan view of the base per se looking in the direction of the line 12-12 of Fig. 10.

The candleholder, according to this invention, includes a one piece body 10 having a U-shaped top portion 10^a formed with a semi-circular grooved inner face 11 for holding adjacent J-shaped candles 12. The body 10 is constructed of porcelain or other similar material and the bottom portion of the U-shaped top portion 10^a continues into a base portion 10^b having a flat bottom which is adapted to be rested upon a table top or other similar surface for supporting the U-shaped top portion 10^a in a position in which the candles 12 will be directed vertically upwards as shown in Fig. 1.

At the bottom the groove 11 is formed with a partition 13 dividing the U-shaped top portion into two halves. The partition 13 is formed with overhanging flanges 14 forming sockets receiving the bottom ends of the J-shaped candles 12. The partition 13 and the overhanging flanges 14 are formed integrally with the U-shaped top portion 10. The candles 12 are adapted to be positioned within the U-shaped top portion in such a manner that the bottom ends thereof will be directed towards each other as shown in Fig. 1, with the ends thereof extending into the space between the top face of the groove and the overhanging flange 14. When the J-shaped candles 12 are in position within the U-shaped top portion the weight of the vertical portion thereof will tend to force the candles 12 into a position in which the bottom ends thereof will bear tightly against the partition 13.

According to the modification of the invention shown in Figs. 4 and 5 the construction of the candleholder is similar to that previously described, except for the provision of a means for holding the candles 12 in different upwardly directed positions, one of these positions being indicated by the dot and dash lines 12' in Fig. 4. The means for accomplishing the adjustment of the candles 12 comprises plates 15 which are adjustably mounted in the bottom portion of the groove 11 and against which the ends of the candles 12 engage. The adjustable mounting of the plates 15 is accomplished by means of elongated slots 16 formed in the sides of the U-shaped top portion 10^a of the body 10. The plates 15 are 55

formed with bosses 15^a in end alignment with the slots 16. Screws 17 are passed through the slots 16 and are threadedly engaged into the ends of the bosses 15^a, as shown in Fig. 5, and are adapted to be tightened in position for maintaining the plates in their proper adjusted positions.

The operation of this form of the invention is as follows:

- 10 When it is desired to shift the position of the candles 12 from the position illustrated by the full lines in Fig. 4 to the position illustrated by the dot and dash lines 12' in Fig. 4, the screws 17 are loosened to permit the plates 15 to be slid 15 along the length of the slots 16 to a position in which the candles 12 will be in the desired adjusted position, whereupon the screws 17 are returned to their normal position for maintaining the candles 12' and the plates 15 in the said desired adjusted position.

According to the modification of the invention shown in Figs. 6 and 7 the candleholder includes a body 20 having a J-shaped top portion 20^a formed with a semi-circular grooved face for holding a J-shaped candle 22. The body 20 is constructed of porcelain or other similar material, and at the bottom end of the J-shaped top portion 20^a it is formed with a member 20^b substantially of cube form for holding a decorative object. The body is further formed with a reinforcing element 20^c which extends between the adjacent side of the member 20^b and the bottom of the J-shaped top portion 20^a.

The bottom end of the J-shaped top portion 20^a is formed with an overhanging flange 23 forming a socket into which the bottom end of the J-shaped candle 22 normally engages. The member 20 is formed with a hollow interior for acting as a flower pot into which a flower 24 may be planted.

According to the modification of the invention shown in Fig. 8 the construction of the candleholder is similar to that described relative to Figs. 6 and 7, except for the provision of a means 45 for holding the candle 22 in different upwardly directed positions. This means is similar to that described in Figs. 4 and 5 and consists of a plate 25 mounted within the bottom end of the J-shaped top portion 20^a and which is adapted 50 to be moved to various adjusted positions. The adjustment of the plate 25 is accomplished by means of screws 26 which pass through elongated slots 27 formed in the sides of the J-shaped top portion 20^a. The inner ends of the screws 26 are threadedly engaged into an elongated boss 25^a formed on the back face of the plate 25 for clamping the plate 25 in various adjusted positions along the length of the slots 27. The bottom end of the candle 22 normally rests against 55 the adjacent face of the plate 25. In this form of the invention the base member 20^{bb} is in a form of a perisphere and the upper end of the candle 22 forms a trylon 22^a.

According to the modification of the invention 60 shown in Fig. 9 the candleholder comprises a J-shaped top element 30 formed with a semi-circular grooved inner face 31 for receiving adjacent J-shaped candles (not shown on the drawings). A base 32 is provided and has a flat bottom 32^a for resting upon a table or other surface 65 for supporting the U-shaped top element in a position in which the candles will be directed vertically upwards therefrom. The means for mounting the U-shaped top element 30 on the base 32 comprises a clip 33 having cylindrical 70

side walls 34 which are adapted to engage into a complementary cylindrical recess 32^b formed in the top face of the base 32. A bridging element 35 is extended between the top edges of the U-shaped top element 30. A screw 36 freely 5 passes through the top face of the clip 33, the bottom portion of the U-shaped top element 30 and threadedly engages the bridge 35 for holding the bridge in position upon the top of the U-shaped element 30 and for holding the U-shaped 10 top element 30 in position upon the clip 33.

This form of the invention is further provided with a means for holding the candles in different upwardly directed positions. This means comprises a pair of plates 37 against which the bottom ends of the candles are adapted to rest. The side walls of the U-shaped top element 30 are formed with elongated slots 38. Screws 39 are passed through the slots 38 and are threadedly engaged into elongated bosses 37^a formed on the back faces of the plates 37 for clamping the plates in various adjusted positions along the length of the slots 38.

According to the modification of the invention shown in Figs. 10-12 inclusive the construction of the candleholder includes a U-shaped top element 40 which is formed with a semi-circular grooved inner face 41 for holding adjacent J-shaped candles 42. A means is provided for holding the U-shaped top portion in position upon a cylindrical plug 43 which in turn is held in position upon a base 44. This means comprises a bridging element 44' which extends across the top edges of the side walls of the U-shaped top element 40. A screw 45 freely passes through the bridging element 44', the bottom of the U-shaped top portion 40 and is threadedly engaged into the cylindrical plug 43. The cylindrical plug 43 is in turn freely engaged into the base 44. The base 44 is formed of separate plies 40 of wood or other similar materials comprising a ply 44^a, a ply 44^b and a ply 44^c. Each of the plies forming the base portions are progressively smaller, with the large ply being located at the bottom. The base 44 is provided with a means 45 for holding the cylindrical plug 43 from rotating within the opening into which it is engaged. This means comprises a key 46 fixedly mounted upon the base 44 and which engages a cutout 43^a formed in the cylindrical plug 43. 50

The base 44 is further provided with a means for preventing any rocking motion of the U-shaped top element 40 and comprises cylindrical members 47 mounted on the top face of the base 44 on either side of the cylindrical plug 43 55 and which engages the top face of the base 44 and a portion of the U-shaped top element 40. The cylindrical members 47 are held in position by means of pins 48 which extend therefrom and which are engaged into the top face of the base 44. When the candles 42 are in position within the U-shaped top element 40 the bottom ends thereof will be engaged beneath the top edges of the bridging element 44' and against the screw 45. 60

It is to be understood that the candleholder may be made of any suitable material such as metal, porcelain, plastics, etc., and the shape as well as the ornamentation may be changed as desired. 65

While we have illustrated and described the preferred embodiments of our invention, it is to be understood that we do not limit ourselves to the precise constructions herein disclosed and the right is reserved to all changes and modi- 70 75
